United States Patent Office.

JOHN PEARD, OF NEW YORK, N. Y.

Letters Patent No. 66,384, dated July 2, 1867.

IMPROVED SCHOOL SETTEE AND DESK.

The Schedule referred to in these Letters Patent and making part of the same.

TO ALL WHOM IT MAY CONCERN:

Be it known that I, JOHN PEARD, of the city, county, and State of New York, have invented a new and improved School Settee and Desk, and that the following description, taken in connection with the accompanying drawings hereinafter referred to, forms a full and exact specification of the same, wherein I have set forth the nature and principles of my said improvements, by which my invention may be distinguished from all others of a similar class, together with such parts as I claim and desire to have secured to me by Letters Patent.

This invention relates to a new and improved combination of a school settee and desk, as hereinafter fully shown and described, whereby a very cheap and durable article of the kind specified is obtained, and one which will admit of being compactly folded when not required for use, and contain both a book and a slate-rack. In the accompanying sheet of drawings—

Figure 1 is transverse vertical section of my invention in a folded state taken in the line *xx*, fig. 3.

Figure 2, a transverse vertical section of the same in an unfolded or distended state taken in the line *yy*, fig. 3.

Figure 3, a plan or top view of the same.

Similar letters of reference indicate like parts.

A A represent the two side pieces of the combined settee and desk. These side pieces are of cast iron, each cast in a single piece, and have bases *a* at their lower ends, through which screws pass into the floor to firmly secure the article in position. B represents the back of the settee, which is of wood, and provided with a top rail, *b*, having a recess or opening, *c*, in it to receive the inkstand. This wooden back is firmly secured between the side pieces, and also an oblong box, C, which serves as a book-rack, and a narrow box, D, directly behind C, which serves as a slate-rack, both boxes being of wood. E represents the desk, also constructed of wood, so as to form a smooth, plane surface, and provided at each side, at its inner end, with metal strips *a* $\times$, having pins *d* to fit into grooves *e* in the inner surfaces of the side pieces A A. These grooves are inclined, as shown in figs. 1 and 2, and the front edge of said groove is rounded at its upper end and inclined slightly from a horizontal position to serve as a support for the desk when drawn out and adjusted for use, the pins bearing against the upper ends of the grooves *e*. (See fig. 2.) When the desk is not required for use it is slipped down between the side pieces A A, as shown in fig. 1, the pins *d* working in the grooves *e*, serving as guides. Thus, by this simple arrangement the desk, when not required for use, may be adjusted out of the way wholly within the compass or space comprised within the side pieces A A. F represents the seat, also constructed of wood, and having metal bars or strips *f* attached to its ends, with a slot, *g*, in each to receive pins *h* at the upper ends of metal supports *G* *G*, the lower ends of which are pivoted to the side pieces A A, as shown at *h*, the bars or strips *f* being pivoted to the side pieces A A, as shown at *g* $\times$.

By this arrangement it will be seen that the seat F may, when not required for use, be raised up out of the way, (see fig. 1,) or turned down when required for use, as shown in fig. 2. The device is extremely simple and efficient, may be very economically constructed, and is extremely strong and durable, there being no parts liable to get out of repair or become deranged by use.

Having thus described my invention, I claim as new, and desire to secure by Letters Patent—

1. The sliding desk E, containing the metallic strips *a* $\times$, arranged in the manner substantially as and for the purpose set forth.

2. The seat F, provided with slotted metal bars or strips *f* at its ends, in combination with the pivoted supports *G* *G*, having pins *h* at their upper ends to work in the slots of the bars or strips *f*, substantially as shown and described.

3. The combination of the sliding desk E with the pivoted seat F and supports *G* *G* and the side pieces A A, all arranged substantially as and for the purpose specified.

4. The book and slate-racks C D, in combination with the desk E; pivoted seat F, and side pieces A A, substantially as and for the purpose set forth.

JOHN PEARD.
